PERFORATION WASHING APPARATUS

Aaron A. Baker, Coalinga, Calif., assignor to
 Baker Oil Tools, Inc., Vernon, Calif., a corpora-
 tion of California

Application June 28, 1948, Serial No. 35,677

17 Claims. (Cl. 166—20)

1

The present invention relates to subsurface well tools, and more particularly to apparatus for cleaning or washing perforated casings, liners and similar conduits located in well bores.

An object of the invention is to provide an apparatus for plugging a perforated conduit string below its perforations and for washing the perforations; the apparatus being capable of performing these operations with a single trip into the conduit string, thereby effecting substantial savings in time and expense.

Another object of the invention is to provide a washer and well packer capable of being run in a perforated conduit string on a single string of tubing; the act of disconnecting the tubing string from the well packer, after the latter has been set in the conduit string, also rendering the washer effective for performing its cleaning function.

A further object of the invention is to provide a perforation washer adapted to be lowered in the casing or similar conduit string, and having a fluid by-pass that can be opened or closed in response to rotation of a tubing string to which the washer is attached.

Still another object of the invention is to provide a perforation washer having a fluid by-pass which can be selectively opened or closed, and which is automatically opened upon elevating the washer within a conduit string.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claims.

Referring to the drawings:

Figure 1 is a side elevation of the perforation washer and well packer apparatus disposed in a perforated string of casing;

Figs. 2 and 2a are longitudinal sections, partly in elevation, of the perforation washer and circulation valve, with their parts disposed in one relative position, Fig. 2a forming a lower continuation of Fig. 2;

Figs. 3 and 3a form a combined longitudinal sectional and elevational view of the apparatus, with the parts in position for washing the casing perforations, Fig. 3a forming a lower continuation of Fig. 3;

2

Figs. 4, 5 and 6 are cross-sections taken along the lines 4—4, 5—5 and 6—6, respectively, of Fig. 2; and

Fig. 7 is a longitudinal section of a modified form of by-pass valve mechanism.

The apparatus disclosed in the drawings is adapted to be run in a well casing A, or similar conduit string, on a string B of tubing, drill pipe, or the like, extending to the top of the well bore. The apparatus includes a perforation washer C at its upper portion in the form of a well packer, an intermediate circulation valve or joint D attached to the lower end of the washer and a well packer E secured to the lower end of the circulation joint.

It is desired to anchor the well packer E in packed-off condition within the well casing A below its perforations 10, and then wash the perforations by pumping washing fluid down the tubing string B for outward passage through the perforations 10 below the washer C to the exterior of the casing string, the washing fluid then passing back into the casing string through the perforations above the washer C, for upward flowing to the top of the well bore.

The well packer may be of any suitable form and type, the one disclosed in the drawing being specifically described in United States Patent No. 2,121,051. Essentially, it consists of a tubular body 11 having upper and lower expanders 12, 13 thereon, and an intervening rubber packing sleeve 14. The upper expander cooperates with upper segmental slips 15, to prevent upward movement of the packer in the well casing; while the lower expander cooperates with lower segmental slips 16, to prevent downward movement of the packer in the casing. The intervening packing sleeve 14 is adapted to be foreshortened and expanded outwardly into leak-proof engagement with the casing wall. Further details of the packer E are unnecessary to an understanding of the present invention, and may be found in the patent above referred to. When set in the casing as a bridging plug, the central passage through the packer body is plugged.

The circulation valve or joint D is attached to the packer body 11 through the agency of a sub 17 having a left hand male thread 18 mating with a companion thread (not shown) in the packer body 11, in a known manner. The sub is secured to a lower circulation joint tubular mandrel 19 telescoped within an outer barrel 20. The barrel has a lower cylindrical valve seat 21 secured to it, in which an internally splined stop member 22 is threaded. This stop member is cooperable with a head 23 on the upper end of the mandrel

19, the head carrying a suitable seal ring 24 adapted to engage within the seat 21 and prevent passage of fluid between the interior and exterior of the circulation valve through the annular space between the mandrel 19 and splined stop member 22.

The mandrel has longitudinally extending splines 25 cooperable with internal splines 26 on the stop member, in order to transmit the rotation of the barrel 20 to the mandrel 19, in effecting unscrewing of the sub 18 from the packer body 11 after the packer has been set in the well casing.

The upper end of the circulation valve barrel 20 is threadedly, or otherwise attached, to the lower end of a tubular inner body or mandrel 27 forming part of the perforation washer or well packer C. The upper end of this mandrel 27 is attached to the lower end of the running-in string B, which extends to the top of the well bore. The mandrel has a tubular outer body 28 threadedly attached to its upper portion, and held thereon by a suitable lock nut 29 threaded on the inner body 27 and clamped against the outer body. The bodies are spaced from each other to form an annular by-pass passage 30 having ports 31 opening outwardly through the outer body 28.

The well packer C includes a downwardly facing rubber packing 32, or swab cup, which is mounted on the outer body 28 below its ports 31, and is adapted to slidably seal with the wall of the well casing A. The base 33 of the packing engages the end of a flared sleeve 34 secured to the lower end of the outer body 28 by suitable welding material 35. The sleeve 34 extends downwardly in spaced relation with respect to a tapered flange 36 on the inner mandrel 27, to form a continuation of the by-pass passage 30. The spaced relation between the flared sleeve 34 and flange 36 may be maintained by welding a spider 37, or spaced lugs, between the two elements. The upper end of the packing cup 32 engages a thimble 38 abutting a clamp nut 39 threaded on the outer body 28, which is prevented from loosening by a suitable lock nut 40.

It is apparent that the by-pass 30 between the inner and outer bodies 27, 28 extends from a point above the downwardly facing packing member 32 to a point therebelow. The lower end of the by-pass is formed as a tapered valve seat 41 on both the flared sleeve 34 and tapered flange 36 for cooperation with a companion valve member 42, in effecting closing of the passage 30, particularly against fluid flow in an upward direction. The companion valve structure 42 includes an annular valve head or ring 43 secured to a depending sleeve 44 by headless screws 45, and having an annular valve sealing element 46 attached to its upper end by screws 47. This annular valve sealing element is engageable with the valve seat 41 to close the by-pass passage.

Movement of the valve head 43 and its seal 46 toward the valve seat 41 is determined by a drag device 48, and is responsive to rotation of the tubing string B and valve body 27. The upper end of the drag device consists of a collar 49 slidably on the depending sleeve 44 and adapted to rest upon a lower sleeve flange 50. The upper ends of circumferentially spaced, outwardly bowed springs 51 are secured to the collar by an encompassing ring 52 and screws 53 passing through the ring and threaded into the collar. The bowed springs drag frictionally along the wall of the casing string A, with their lower ends secured to a lower internally threaded collar 54 75

by means of an encompassing ring 55 and screws 56. This lower sleeve is in threaded engagement with an inner sleeve 57 disposed on the mandrel 27 and prevented from moving longitudinally thereof by upper and lower snap rings 58 engaging its upper and lower ends and received within external grooves 59 in the mandrel. This sleeve is non-rotatably held on the mandrel by a key 60 in the mandrel extending into a keyway 61 in the sleeve.

The valve head 43 is urged toward its companion seat 41 by a helical spring 62 disposed around the mandrel, with its upper end engaging the depending sleeve 44 and with its lower end bearing upon a spring seat or spacer sleeve 63 resting upon the inner threaded sleeve 57. The spring is compressed and is initially prevented from moving the head 43 into engagement with the valve seat 41 by virtue of the engagement of the sleeve flange 50 with the lower end of the upper drag collar 49. The drag collar 49 occupies an initial lower position because of the fact that the lower drag collar 54 is initially assembled so as to be disposed on the lower threaded portion of the inner sleeve 57. It is to be noted, however, that the valve head 43, although its upward movement is limited by engagement of the sleeve flange 50 with the upper collar 49, can move downwardly with respect to the latter member, because of the clearance space existing between the lower end of the head 43 and the upper end of the collar 49.

The apparatus is lowered in the perforated well casing A on the end of the tubular string B, with the lower drag collar 54 mounted on the lower end of the inner sleeve 57, which causes the upper collar 49 to hold the valve in open position, as disclosed in Fig. 2. The circulation joint D is attached to the washer mandrel 27, which is, in turn, secured to the well packer E through the agency of the left hand threaded tubular sub 17. The slips 15, 16 and packing sleeve 14 of the packer are in retracted positions.

The apparatus is lowered through the well casing A until the packer E is disposed below the perforated portion of the casing string, whereupon the slips 15 and packing 16 are expanded outwardly against the casing in a known manner, described in the aforesaid United States patent, to form a bridge or plug in the well casing preventing downward passage of fluid. During lowering movement of the apparatus through the well casing, its downward passage is not prevented by any fluid therein, since such fluid can move around the rubber packing cup 32 by flowing through the open by-pass 30.

After the packer is anchored in the casing, the tubing string B is rotated to the right to effect disconnection of the left hand threaded sub 17 from the packer body 11. The rotation of the tubing string B is transmitted to the sub 17 through the washer mandrel or body 27, outer circulation valve barrel 20, cooperable splines 26, 25 and mandrel 19, the telescopic circulation valve allowing the threaded disconnection to occur readily since the unthreading action merely elevates the mandrel 19 within the barrel 20 without any of the load of the running-in string or perforation washer being imposed on the left hand threads 18.

During this rotation of the washer mandrel 27 in effecting disconnection of the sub 17 from the packer body 11, the inner threaded sleeve 57 is also rotated within the lower collar 54, the latter being prevented from rotating by the fric-

tional engagement of the outwardly bowed springs 51 with the casing wall. Since the threaded connection between the inner sleeve 57 and the lower collar 54 is a right hand thread, the rotation of the mandrel 27 to the right, or clockwise, will effect relative upward threading of the lower collar 54 on the inner sleeve 57, and will correspondingly shift the upper drag collar 49 toward the valve seat 41, allowing the spring 62 to engage the valve head seal 46 with the seat 41 and close the by-pass 30 against upward flow of fluid (Fig. 3). The motion just referred to is a relative one. As a matter of fact, the drag device 48 and its collars 49, 54 may remain stationary, the rotating of the tubular mandrel 27 allowing the tubing string B and inner and outer bodies 27, 28 to be lowered a sufficient distance relative to the drag device 48 to move the valve seat 41 into engagement with the valve head seal 46. The threaded connection between the inner sleeve 57 and lower collar 54 may be considered as a form of axial cam effecting axial movement of the collar 54 upon rotation of the sleeve 57.

With the passage 30 closed against upward flow of fluid, the casing perforations 10 can now be washed. The tubing string B is lowered to locate the swab cup 32 immediately above a lowermost perforated casing region, and washing fluid pumped down the tubing string for outward passage through the circulation valve D or left hand sub 17, this fluid then flowing through the perforated casing portions below the packing cup into the annulus around the casing string. Any particles that may have been plugging the casing perforations 10, or any loose materials behind the casing string are flushed upwardly along the exterior of the casing to a point above the packing cup, where they can re-enter the casing through the perforations 10 and flow upwardly through the tubing-casing annulus to the top of the well bore. Sufficient pressure can be applied to the fluid to insure thorough cleaning of the perforations 10. It is to be noted that the packing cup 32 prevents flow of fluid between the outer body 28 and casing A; while the upwardly seating valve member 43 closes the by-pass 30 against upward passage of fluid. The only course that the washing liquid can pursue is the one described above, namely, out through the perforations 10 below the packing 32, up along the exterior of the casing string, and back into the casing through the perforations 10 above the packing cup 32.

After a lower section of perforations is cleaned, the tool may be elevated and the next adjacent group of perforations cleaned in the foregoing manner until the entire perforated casing section has been thoroughly washed. The washer is now removed from the well bore, its elevation being unhampered by the liquid in the well casing since such liquid can flow downwardly through the by-pass 30, unseating the valve 43 against the action of the spring 62, some of the liquid also flowing downwardly around the exterior of the packing cup 32. It is evident that the by-pass valve is in the nature of a check valve, or one-way valve, allowing relative downward passage of fluid through the by-pass merely as an incident of elevating the tubing string B and without the necessity for otherwise manipulating the tubing string to effect opening or closing of the by-pass.

A modified form of by-pass valve device is shown in Fig. 7, in which it is desired to insure

against plugging of the passage 30 by detritus, rubber particles, or other foreign substances in the well bore.

In this form of the invention, a spider, having an inner sleeve portion 36a mounted on the inner body 27 and spaced lugs 37a engaging the flared sleeve 34a, is welded to the inner body 27 by suitable welding material 70. The lower ends of the spaced sleeves 36a, 34a are rounded or beveled to form concentric valve seats 41a adapted to be engaged by an annular flat rubber valve sealing element 46a secured to the valve head 43a by cap screws 47 and washers 71. The space 72 between the valve head seal 46a and seats 41a is screened by a cylindrical perforated member 73 attached to the valve head 43a in any suitable manner, as by the screws 45 securing the valve head to the depending sleeve 44. This screen extends upwardly for engagement with the periphery 74 of the flared sleeve 34a, the engagement being maintained at all times.

It is evident that any fluid passing upwardly through the by-pass must flow through the screen 73, whose perforations 75 are small enough to prevent large size particles from passing into the by-pass and possibly plug it. In all other respects, the valve mechanism functions in the same manner as the other form of the device.

The inventor claims:

1. In apparatus of the character described: a well packer adapted to be set in a conduit string positioned in a well bore; a perforation washer detachably secured to said packer, said washer having a conduit engaging packing element and a by-pass around said element, said by-pass having a valve seat; said washer having valve means engageable with said seat; means engageable with said valve means and disposed normally in a position holding it off said seat; and means operatively connected to said holding means and washer to hold said holding means in said position and movable by said washer, upon movement of said washer to disconnect said washer from said packer, to shift said holding means to another position allowing said valve means to engage said seat.

2. In apparatus of the character described: a first well packer adapted to be set in a conduit string positioned in a well bore; a second well packer above said first packer adapted to be lowered in said conduit string on a tubular running-in string for sealing engagement with the conduit string; means detachably connecting said second packer to said first packer; said second packer having a packing element engageable with said conduit string and a by-pass around said packing element, said by-pass having a valve seat; valve means movable to and from said seat to control fluid flow through said by-pass; and means operatively connected to said valve means to hold said valve means in a position off its seat and responsive to rotation of said tubular string in disconnecting said second packer from said first packer for effecting shifting of said valve means to another position in engagement with said seat to close said by-pass.

3. In apparatus of the character described: a first well packer adapted to be set in a conduit string positioned in a well bore; a second well packer above said first packer adapted to be lowered in said conduit string on a tubular running-in string for sealing engagement with the conduit string; means detachably connecting said second packer to said first packer, rotation of said second packer relative to said first packer

disconnecting it from said first packer; said second packer having a packing element engageable with said conduit string and a by-pass around said packing element, said by-pass having a valve seat; valve means movable to and from said seat to control fluid flow through said by-pass; and means operatively connected to said valve means to hold said valve means in a position off its seat and responsive to rotation of said tubular string and second packer for effecting longitudinal shifting of said valve means to another position in engagement with said seat to close said by-pass.

4. In apparatus of the character described: a first well packer adapted to be set in a conduit string positioned in a well bore; a second well packer above said first packer adapted to be lowered in said conduit string on a tubular running-in string for sealing engagement with the conduit string; means detachably connecting said second packer to said first packer, rotation of said second packer relative to said first packer disconnecting said second packer from said first packer; said second packer having a packing element engageable with said conduit string and a by-pass around said packing element, said by-pass having a valve seat; valve means movable to and from said seat to control fluid flow through said by-pass; conduit engaging means engageable with said valve means and normally disposed in a position holding said valve means in open position; and means operatively connected to said conduit engaging means and second packer to hold said conduit engaging means in said position and for shifting said conduit engaging means to another position permitting movement of said valve means into engagement with said seat to close said by-pass upon rotation of said second packer in effecting disconnection of said second packer from said first packer.

5. In apparatus of the character described: an outer tubular member adapted to be positioned in a well conduit string; a packing on said member for sealing with the well conduit; an inner tubular member spaced from said outer member to form a by-pass around said packing, said by-pass having a valve seat; a valve member on said inner member movable upwardly into engagement with said seat to close said by-pass; means engageable with said conduit string and valve member and normally disposed in a position holding said valve member in open position with respect to said seat; and means providing an axial cam interconnection between said holding means and inner tubular member to hold said holding means in said position and to enable rotation of said inner tubular member relative to said holding means to shift said holding means relatively longitudinally along said inner tubular member to another position permitting said valve member to engage said seat and close said by-pass.

6. In apparatus of the character described: tubular means adapted for connection to a tubular string for running said tubular means in a well conduit; a packing on said tubular means for sealing with the well conduit; said tubular means having a by-pass extending around said packing, said by-pass having a valve seat; valve means on said tubular means for controlling fluid flow through said by-pass; means engageable with said valve means and normally disposed in a position holding said valve means in open position; and means providing an axial cam interconnection between said holding means and tubular means to hold said holding means in said

position and to enable rotation of said tubular means relative to said holding means to produce shifting of said holding means relatively longitudinally along said tubular means to another position allowing said valve means to engage said seat and close said by-pass.

7. In apparatus of the character described: tubular means adapted for connection to a tubular string for running said tubular means in a well conduit; a packing on said tubular means for sealing with the well conduit; said tubular means having a by-pass extending around said packing, said by-pass having a valve seat; a valve member slidably along said tubular means for controlling fluid flow through said by-pass; means engageable with said well conduit and valve member and normally disposed in a position holding said valve member in open position with respect to said seat; and means providing an axial cam interconnection between said holding means and tubular means to hold said holding means in said position and to enable rotation of said tubular means relative to said holding means to produce shifting of said holding means relatively longitudinally along said tubular means to another position allowing said valve member to engage said seat and close said by-pass.

8. In apparatus of the character described: tubular means adapted for connection to a tubular string for running said tubular means in a well conduit; a packing on said tubular means for sealing with the well conduit; said tubular means having a by-pass extending around said packing, said by-pass having a valve seat; a valve member movable upwardly along said tubular means into engagement with said seat to close said by-pass; a drag device engageable with said valve member and normally disposed in a position holding it in a position opening said by-pass; and means providing an axial cam interconnection between said drag device and tubular means to hold said drag device in said position and to enable rotation of said tubular means relative to said drag device to produce shifting of said drag device relatively longitudinally along said tubular means to another position allowing said valve member to engage said seat and close said by-pass.

9. In apparatus of the character described: tubular means adapted for connection to a tubular string for running said tubular means in a well conduit; a packing on said tubular means for sealing with the well conduit; said tubular means having a by-pass extending around said packing, said by-pass having a valve seat; a valve member slidably along said tubular means; spring means around said tubular means for urging said valve member upwardly into engagement with said valve seat to close said by-pass; means engageable with said valve member and normally disposed in a position holding said valve member in open position with respect to said valve seat; and coengaging threaded means on said tubular means and holding means for relatively shifting said holding means longitudinally of said tubular means to another position upon rotation of said tubular means relative to said holding means, thereby allowing said spring means to shift said valve member into engagement with said valve seat.

10. In apparatus of the character described: tubular means adapted for connection to a tubular string for running said tubular means in a well conduit; a packing on said tubular means for sealing with the well conduit; said tubular means

having a by-pass extending around said packing, said by-pass having a valve seat; a valve member slideable along said tubular means; spring means around said tubular means for urging said valve member upwardly into engagement with said valve seat to close said by-pass; means engageable with said valve member and conduit string and normally disposed in a position holding said valve member in open position; and means providing an axial cam interconnection between said holding means and tubular means to hold said holding means in said position and to enable rotation of said tubular means relative to said holding means to shift said holding means relatively longitudinally along said tubular means to another position allowing movement of said valve member into engagement with said seat to close said by-pass.

11. In apparatus of the character described: tubular means adapted for connection to a tubular string for running said tubular means in a well conduit; a packing on said tubular means for sealing with the well conduit; said tubular means having a by-pass extending around said packing, said by-pass having a valve seat; a valve member slideable along said tubular means; spring means around said tubular means for urging said valve member upwardly into engagement with said seat to close said by-pass; means engageable with said valve member and conduit string for holding said valve member off said seat and in open position; and coengaging threaded means on said tubular means and holding means for relatively shifting said holding means longitudinally to ineffective position upon rotation of said tubular means, thereby allowing said spring means to shift said valve member into engagement with said seat to close said by-pass.

12. In apparatus of the character described: tubular means adapted for connection to a tubular running-in string; a packing on said tubular means for sealing with the well conduit; said tubular means having a by-pass extending around said packing, said by-pass having a valve seat; a valve member slideable along said tubular means; spring means around said tubular means for urging said valve member upwardly into engagement with said seat to close said by-pass; a drag device including an upper collar engageable with said valve member for holding said valve member off its seat and in open position, a lower drag collar and outwardly bowed springs connected to said collars and frictionally engageable with said well conduit, said lower drag collar being internally threaded; and a member fixed to rotate with said tubular means and threadedly engaging said lower drag collar, whereby rotation of said tubular string will effect relative shifting of said drag device longitudinally of said tubular means to render said upper drag collar ineffective to hold said upper valve member off its seat.

13. In apparatus of the character described: a first well packer adapted to be set in a conduit string positioned in a well bore; a second well packer above said first packer adapted to be lowered in said conduit string on a tubular running-in string for sealing engagement with the conduit string; means providing a detachable left-hand threaded connection between said packers; said second packer having a packing element engageable with said conduit string and a by-pass around said packing element, said by-pass having a valve seat; valve means movable to and from said seat to control fluid flow

through said by-pass; means engageable with said valve means and normally disposed in a position holding said valve means in open position with respect to said seat; and means engaging said holding means to hold said holding means in said position and responsive to rotation of said tubular string in unthreading said second packer from said first packer for shifting said holding means to another position allowing said valve means to engage said seat and close said by-pass.

14. In apparatus of the character described: a first well packer adapted to be set in a conduit string positioned in a well bore; a second well packer above said first packer adapted to be lowered in said conduit string on a tubular running-in string for sealing engagement with the conduit string; means detachably connecting said second packer to said first packer; said second packer having a packing element engageable with said conduit string and a by-pass around said packing element, said by-pass having a valve seat; a valve member on said second packer movable upwardly into engagement with said seat to close said by-pass; means engageable with said conduit string and valve member and normally disposed in a position holding said valve member in a lower and open position with respect to said seat; and means engaging said holding means to hold said holding means in said position and responsive to rotation of said tubular string in disconnecting said second packer from said first packer for shifting said holding means to another position allowing said valve means to move upwardly into engagement with said seat to close said by-pass.

15. In apparatus of the character described: a well packer adapted to be set in a conduit string positioned in a well bore; a perforation washer detachably secured to said packer, said washer having a conduit engaging packing element and a by-pass around said packing element, said by-pass having a valve seat; said washer having valve means movable longitudinally into and out of engagement with said seat; means engageable with said valve means and disposed normally in a position holding it off said seat; and means operatively connected to said holding means and washer to hold said holding means in said position and movable longitudinally by said washer, upon movement of said washer to disconnect said washer from said packer, to shift said holding means longitudinally to another position allowing said valve means to move longitudinally into engagement with said seat.

16. In apparatus of the character described: a first well packer adapted to be set in a conduit string positioned in a well bore; a second well packer above said first packer adapted to be lowered in said conduit string on a tubular running-in string for sealing engagement with the conduit string; means detachably connecting said second packer to said first packer, rotation of said second packer relative to said first packer disconnecting it from said first packer; said second packer having a packing element engageable with said conduit and a by-pass around said packing element, said by-pass having a valve seat; valve means movable axially to and from said seat to control fluid flow through said by-pass; conduit engaging means engageable with said valve means and normally disposed in a position holding said valve means longitudinally spaced from said seat to maintain said by-pass in open condition; and means operatively con-

11

nected to said conduit engaging means and second packer to hold said conduit engaging means in said position and for shifting said conduit engaging means axially to another position permitting axial movement of said valve means into engagement with said seat upon rotation of said second packer in effecting disconnection of said second packer.

17. In apparatus of the character described: a first well packer adapted to be set in a conduit string positioned in a well bore; a second well packer above said first packer adapted to be lowered in said conduit string on a tubular running-in string for sealing engagement with the conduit string; means providing a detachable left-hand threaded connection between said packers; said second packer having a packing element engageable with said conduit string and a by-pass around said packing element, said by-pass having a valve seat; valve means movable lengthwise of the axis of said seat and to and from said seat to control fluid flow through said by-pass; means engageable with said valve means for holding said valve
